SOLOMON LUBER AND MAX EIBETZ, OF NEW YORK, N. Y.

PYROPHORIC IGNITING DEVICE.

1,394,917.

Specification of Letters Patent. Patented Oct. 25, 1921.

Application filed October 25, 1919. Serial No. 333,254.

To all whom it may concern:

Be it known that we, SOLOMON LUBER and MAX EIBETZ, citizens of Poland and the United States, respectively, and residents 5 of New York, in the counties of New York and Kings, respectively, and State of New York, have invented certain new and useful Improvements in Pyrophoric Igniting Devices, of which the following is a specification.

The present invention relates to igniting-devices, and more particularly to pocket igniting-devices, including means for producing sparks by the abrasion of a pyrophoric body.

In one type of these devices, the sparking element is held in engagement with a combined thumb wheel and friction disk, that is rotated in the proper direction by 20 the thumb of the user, to produce a spark. This friction disk is provided with a milled periphery, against which the sparking element is held by a spring. In order to rotate the friction disk, the thumb is placed 25 against the milled periphery thereof and moved toward the casing of the implement. Due to the fact that the wheel is under the action of a spring, it is very hard to turn, and its milled peripheral portion is thus 30 apt to injure the thumb.

The main object of the present invention is to obviate these defects of the devices heretofore in use, by attaching to the cover of the casing an element, that imparts rotation to the friction disk, when removed 35 from the casing.

Another object of the invention is to produce a pocket igniting device of the type mentioned which is simple in construction, 40 efficient in operation and which can be manufactured on a commercial scale, or in other words one which is not so difficult to make as to be beyond the reasonable cost of such a contrivance.

With these and other objects in view, which will more fully appear as the nature of the invention is better understood, the same consists in the combination, arrangement and construction of parts hereinafter 45 described, pointed out in the appended claim and illustrated in the accompanying drawings, it being understood that many changes may be made in the size and proportion of the several parts and details of construction within the scope of the appended claim 50

without departing from the spirit or sacrificing any of the advantages of the invention.

A few of the many possible embodiments of the invention are illustrated in the accompanying drawings, in which:—

Figure 1 is a side elevation, partly in section, of a pocket igniting device constructed in accordance with the present invention; Fig. 2 is a similar elevation of the same, showing the cover in a position 60 to actuate the friction disk thereof; and Figs. 3 to 5, inclusive, are vertical central sections taken through modified covers.

Referring now first to Figs. 1 and 2 of the drawings, the numeral 10 indicates a 70 closed casing, having a reduced upper end 11, onto which fits a cover 12. The casing is provided with a wick tube 13, adapted to expose at its upper end a wick 14, that is saturated with a volatile liquid hydrocarbon. A tubular guide 15 extends substantially parallel with the wick tube, its upper end forming lugs 16 in proximity to the upper end of the wick tube, and in this guide is disposed a pyrophoric body 17, that 75 is held by a spring (not shown) against the milled peripheral face of a friction disk 18, the latter being rotatably mounted in the lugs 16. The friction disk is mounted to rotate in a plane passing longitudinally 80 through the wick tube. Thus far described, the function and operation of the elements are well-known, so that a detailed description of the same is deemed to be unnecessary.

Within the cover 12 is disposed a blade spring 19, having a downwardly extending roughened portion 20, abutting against the milled periphery of the friction disk. The free end of the spring is bent outwardly, as 95 shown at 19', for a purpose that will appear hereinafter. A portion of the spring, denoted by the numeral 21, rests against the inner face of the top portion of the cover, a rivet 22 passing through the spring and the top portion of the cover, to hold the spring in proper position.

The operation of this device is as follows:—In order to produce a spark, the cover is first moved on the casing in the direction of the longitudinal axis of the latter, and given a partial turn as soon as it is adapted to clear the reduced portion 11 of the casing (Fig. 2). In this manner, the spring imparts a rotation to the friction 100 disk 18, which is continued until the pyrophoric body 17 is abraded by the milled peripheral face of the friction disk. The wick 14 is 105

disk in the direction of the arrow shown in Fig. 2 of the drawings, thereby producing sparks by abrasion of the pyrophoric body, said sparks flying toward the wick and igniting the same. No difficulty is experienced in replacing the cover, since the free end of the spring is curved away from the friction disk, so that the latter easily finds its place.

10 Instead of using a rivet for attaching the spring to the cover, a lug 23 may be stamped out from the body portion of the spring (Fig. 3). This lug is extended through an aperture 24 in the cover and its free end provided with a head 25, that abuts against the outer face of the cover.

Another method of securing the spring to the cover is illustrated in Fig. 4 of the drawings, in which the spring is provided 20 with outwardly extending projections 26, fitting into depressions 27 in the cover.

The spring may be secured to the cover by forming upon opposite portions of the latter inwardly extending projections 28, 25 that bear against the spring, (Fig. 5).

It is to be observed that, while herein several ways of fastening the spring to the cover of the implement are shown, others

may just as well be used without departing from the invention, which lies mainly in the provision of a springy body, that bears against the friction disk and is adapted to rotate the same in the proper direction upon removal of the cover from the casing of the implement.

35 What we claim is:—

A pocket igniting device comprising a casing having a reduced upper end, of a removable cover fitting said reduced end, a wick tube in said casing adapted to expose 40 a wick at its upper end, a friction disk mounted to rotate in a plane passing longitudinally through the wick tube and located adjacent the end of the wick tube, a sparking element held in engagement with said friction disk, and a spring attached to said cover having a roughened surface portion in abutment with said friction wheel adapted to rotate the latter upon removal of said cover 45 from said casing.

50 Signed at New York, in the county of New York and State of New York, this 14th day of May, A. D. 1919.

SOLOMON LUBER.
MAX EIBETZ.
